UNITED STATES PATENT OFFICE.

CARL SPEISER, OF GELTERKINDEN, NEAR BASEL, SWITZERLAND.

LOOM.

1,317,737.

Specification of Letters Patent.

Patented Oct. 7, 1919.

Application filed March 23, 1918. Serial No. 224,239.

To all whom it may concern:

Be it known that I, CARL SPEISER, a citizen of the Swiss Republic, and resident of Gelterkinden, near Basel, Switzerland, have 5 invented new and useful Improvements in Looms, of which the following is a full, clear, and exact specification.

The invention relates to a loom in which the warp is obliquely upright and the heddles 10 for forming the shed, instead of being suspended, are in an inclined or oblique position and have the form of rigid harness frames sliding in a guide frame, while the lay is arranged below the heddles and moves 15 in an upwardly inclined direction, instead of horizontally.

In such a loom the warp is most conveniently inspected and easily accessible, which is very advantageous for the weaver in respect 20 both of health and labor. Moreover, since the heddles are not suspended the numerous heddle cords, wires and the like are eliminated and the weight of the heddles is to a great extent without effect, so that 25 they can be moved more quickly than suspended heddles. Further, as the lay is arranged below the heddles, the latter are easily accessible and visible. Finally, the loom can in many cases be better arranged 30 in the mill than formerly and more easily superintended.

The new construction of loom is appropriate for all kinds of yarn, wool, cotton, silk, waste silk, flax, paper or the like. It is 35 applicable for cloth looms or for ribbon looms of any ribbon breadth, and for all kinds of fabric, such as taffeta, figured fabric, velvet or the like.

The accompanying drawings show, as an 40 example of the invention, a ribbon loom having a tappet motion for the heddles.

Figure 1 is a vertical section through the loom.

Fig. 2 is a plan of the tappet shaft and 45 its driving mechanism.

Fig. 3 is a longitudinal section from top to bottom through the harness frames and also shows the tappet levers lying behind the frames.

50 Fig. 4 shows in plan half of one of the harness frames, drawn to an enlarged scale.

Fig. 5 is a part section, drawn to a still larger scale, through one of the harness frames and through the guide frame.

55 Fig. 6 is a section on line A—B of Fig. 5. The obliquely directed warp is designated

at 1 and the shed is at 2. The heddles, are arranged in an inclined position one above the other and are formed by rigid harness frames 3 (Figs. 4, 5, 6) which are guided 60 rectilinearly in a guide frame 5. At their forward ends the harness frames 3 are grooved to receive heddle frames 6 which are pushed into place and are retained by spring catches 7 that can be operated by 65 hand to permit withdrawal of the heddle frame. The heddles in the heddle frames have the usual eyes through which the warp threads are threaded according to the number of ribbons and to the kind of shedding 70 in the well-known manner so that those threads of the different ribbons which are to share the same shed extend through eyes of heddles in the same heddle frame.

The harness frames are moved for example 75 by a tappet motion. The mechanism here shown comprises, as usual, a number of tappet levers 8 corresponding with the number of harness frames and connected with them respectively by rods 9; in Fig. 1 only the 80 last lever at each end of the row is shown, for the sake of clearness. The connection of the several tappet levers 8 with the corresponding harness frames 3 is shown diagrammatically at 10, Fig. 3. The levers 8 85 are mounted to turn on an inclined shaft 11 suitably arranged in the lower part of the loom, and each is subject to the action of a spring 12 and a tappet 13. The shaft 11 being inclined and the tappet levers 8 of different 90 lengths, the point of contact of each tappet on its lever is such that the harness frame connected with each lever receives the stroke necessary for proper formation of the shed; that is to say, the stroke of the upper harness 95 frames which are farther from the fell of the cloth is greater than that of the lower frames, in order to form a clean shed. The tappets 13 are fixed to a shaft 14 (Fig. 2) which is transversely divided; the tappets 100 forming two groups on this shaft, those of one group, for instance those used for grounding, being connected with one half of the shaft by means of a collar 15 fixed thereon and of coupling bolts 16 carried by said 105 collar, while those of the other group, for instance those used for border formation, are connected by means of another collar 17 and coupling bolts 18 with the other half of the shaft. The halves of the shaft 14 are each 110 driven by a separate toothed gearing 19, 20 of variable ratio, and through two bevel

wheel gears 21, 22 from two intermediate shafts 23, 24 which in their turn are driven through bevel gears 25, 26 by a common shaft 27 receiving its motion from the driving pulley 29 through toothed gearing 28. This arrangement permits of bringing the two groups of tappets into the desired relationship in respect of their rotation for the shedding work.

10 The strokes which the levers 8 perform under action of the springs 12 is adjustable by screw stops 43.

The lay 30, instead of moving to and fro in a more or less substantially horizontal plane, moves up and down in an upwardly inclined direction. It is placed below the harness frames and rocked on an axis 31 by a grooved eccentric 32, which, for the purpose of a prolonged open shed, is driven in known manner by means of a pair of eccentrically journaled toothed wheels 33. The weight of the lay is for the most part borne by the corresponding springs 44 fixed to the frame of the loom. The throw of the shuttle is not new; any desired kind of mechanism may be used and therefore none is shown in the drawings. It may, however, be stated that the shuttle will be slidably connected with the raceway of the lay by means of a known groove and claw connection so as to be prevented from falling out of place. The beating of the weft takes place below the harness frames, at 34.

The ribbons may pass around the drum 35 which in conjunction with the pressure roller 36 and the counter-roller 37 exerts the pull on the ribbons and allows them to run on to a friction drum 38. The lower part of the loom, however, offers sufficient space 40 for a friction reel 39 on to which the ribbons can run if necessary.

Fig. 1 shows two modes of delivering the warp threads. One consists of spools 40, the other of warp rollers 41. From either store 45 of warp the threads are drawn downward, with hardly any contact or friction, over the guide rods 42.

What I claim is:

1. In a weaving loom, having an oblique warp arrangement, rigid harness frames for shedding arranged in an oblique position, a guide frame for slidably guiding said harness frames and a lay placed below the harness frames and arranged to move up and down in an oblique direction, substantially as described.

2. In a weaving loom, having an oblique warp arrangement, rigid harness frames for shedding arranged in an oblique position, 60 said harness frames being provided with side grooves, removable heddle frames engaged into the side grooves of the harness frames, a releasable catch device for holding the heddle frames in the grooves of the harness frames, a guide frame for slidably guiding said harness frames, and a lay placed below the harness frames and arranged to move up and down in an oblique direction, 65 substantially as described.

3. In a weaving loom, having an oblique warp arrangement, rigid harness frames for shedding arranged in an oblique position, a guide frame for slidably guiding said harness frames, a tappet mechanism for moving said harness frames, said tappet mechanism comprising two groups of tappets for two different kinds of shedding mounted on a two-part shaft, one group being connected with one part of the said shaft and the other with the other shaft part, and an own drive 75 device for each shaft part, a lay placed below the harness frames and arranged to move up and down in an oblique direction, 80 substantially as described.

4. In a weaving loom, an oblique warp arrangement, rigid harness frames for shedding arranged in an oblique position one above the other, a guide frame for slidably guiding said harness frames, a tappet mechanism for moving said harness frames, 85 said tappet mechanism comprising two groups of tappets for two different kinds of shedding mounted on a two-part shaft, one group being connected with one part of the said shaft and the other with the 90 other shaft part, an own drive device for each shaft part, a plurality of tappet levers arranged to be operated by said tappets, an inclined shaft for supporting the said tappet levers and connection means between 95 said tappet levers and the rigid harness frames, a lay placed below the harness frames and arranged to move up and down in an oblique direction, substantially as described.

In witness whereof I have hereunto signed my name this 2d day of March, 1918, in the presence of two subscribing witnesses.

CARL SPEISER.
